(57) **CLAIM**

The ornamental design for a LED photon physiotherapy instrument, as shown and described.

DESCRIPTION

FIG. 1 is a front, right and top perspective view of a LED photon physiotherapy instrument, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the LED photon physiotherapy instrument in another state, wherein the cover is separated from the LED photon physiotherapy instrument.

The broken lines depict portions of the LED photon physiotherapy instrument that form no part of the claimed design.

1 Claim, 9 Drawing Sheets
